UNITED STATES PATENT OFFICE.

ROBERT J. WARD, OF PHILADELPHIA, PENNSYLVANIA.

ELECTROLIER STRUCTURE.

1,362,206.

Specification of Letters Patent. Patented Dec. 14, 1920.

Application filed January 17, 1920. Serial No. 351,986.

To all whom it may concern:

Be it known that I, ROBERT J. WARD, a citizen of the United States, residing at Philadelphia, in the county of Philadelphia and State of Pennsylvania, have invented 5 certain new and useful Improvements in Electrolier Structures, of which the following is a specification.

One object of my invention is to provide 10 an improved electrolier which will include as a part thereof an ornamental depending tassel which incloses means for readily connecting various electrical devices thereto in order to supply electric current to said 15 devices. For example the tassel of my improved electrolier provides an ornamental fixture to which can be attached connecting plugs of wires for table lamps, vacuum cleaners, electric irons or any other electric 20 device which is often required to be temporarily connected to a current supply.

Another object is to so make my invention 25 that the tassel forms an ornamental element in the design of the electrolier when being used or not being used as a means of electric connection, and does away with the necessity of using one of the main lamp 30 sockets of an electrolier as an auxiliary connection, as is usually the custom when connecting devices, such as above described, to an electrolier.

A further object is to so construct my invention that dirt is prevented from collecting 35 within the tassel or on the electric connecting members since when not being used for connecting purposes, the bottom of the tassel is closed by a cap, and when being used for connecting purposes the connecting plug will serve to cover the end of the tassel and said connecting members.

A further object is to make my invention 40 of a strong and durable construction so that it can be practically used without injury to the electrolier or connected parts.

45 These objects, and other advantageous ends which will be described hereinafter, I attain in the following manner, reference being had to the accompanying drawings in which

50 Figure 1 is an elevation showing my invention when connected to a table lamp.

Fig. 2 is a sectional elevation of my improved tassel and its connecting parts show-

ing the same when serving as a source of electric supply, 55

Fig. 3 is an outside elevation showing my improved tassel and its connecting elements to the remaining portion of the electrolier; the same showing the tassel in its normal condition, 60

Fig. 4 is a fragmentary transverse section taken on the line 4—4 of Fig. 2,

Fig. 5 is a fragmentary elevation showing the bottom of the tassel closed with the cap, and 65

Fig. 6 is a fragmentary elevation showing an instance where the cap is hinged to the body portion of the tassel and may be swung without entire detachment into an open position to permit the insertion of a connecting 70 plug; the cap being shown closed in full line position and open in dot-and-dash line position.

Referring to Figs. 1 to 5 inclusive, 7 represents an electrolier which is adapted to 75 be suspended from a ceiling 8; the same including chains 9 which support a body portion 10. This body portion 10 in the present instance is made in the form of a bowl or dome having lateral projections 11 upon 80 which are suspended depending electric lamps 12 adjacent the periphery of the dome 10. The dome 10 has a central depending extension 13 which is provided with an eyelet 14 in which is hung a ring 15. The ring 85 15 also extends through the looped head 16 of a tassel 17. The tassel 17 includes a shell 18 which may be made of metal or other material.

A tube 19, which may be made of a short 90 piece of pipe, has an upper screw threaded end 20 which fits a tapped hole 21 in the upper end of the shell 18. A portion of the screw threaded end 20 fits within a tapped recess 22 in the bottom of the looped head 95 16. The opening 23 in the looped head 16 extends to said recess 22 and is in communication with the interior of the tube 19. Further than this, the bottom of the head 16 preferably abuts the top of the shell 18, 100 as clearly shown in Fig. 2. The lower end of the tube 19 is screw threaded and fits within the top of an insulator 24; said insulator being preferably made of porcelain or other material which is a non-conductor 105 of electricity. The bottom of the shell 18

is provided with an inturned flange 25 providing a central hole 26. The insulator 24 is located within the shell 18 and includes an internally screw threaded metallic bushing 27 which is electrically connected by one strand 28 of an electric wire; the other strand 29 of said electric wire being connected to a contacting finger 30 which is insulated from the bushing 27 and in the 10 present instance leads to a position centrally within the space provided by said bushing.

The strands 28 and 29 extend upwardly through the insulator 24 and tube 19 and outwardly through the opening 23 of the 15 looped head 16. This wire can then be threaded through the ring and upwardly into the body portion or dome of the electrolier from where it can pass upwardly through the ceiling 8 in the usual manner 20 and may be connected to the same wires which supply current to the lamps 12. Under normal conditions the hole 26 in the bottom of the shell 18 is closed by a flange 31 of a cap 32; said cap having a screw 25 threaded stem 33 which is adapted to be screwed upwardly within the bushing 27. This cap may be made of metal and as such the stem 33 will necessarily have to be made of such height as not to engage the contacting 30 finger 30. Figs. 3 and 5 show the cap 32 in the position as just described and forming a closure for the hole 26 and interior of the bushing 27.

The outer surface of the shell 18 is provided with ribs or projections which correspond to or have the appearance of cords constituting a tassel. In similar manner the outer surface of the cap 32 is provided with ribs or other markings corresponding to the 40 bottom portion of a tassel, as clearly evidenced in Figs. 1 and 3. When it is desired to electrically connect a device such for example as the table lamp 34 shown in Fig. 1, the plug 35 of the feed wire 36 to the lamp 34 is screwed into the bushing 27 after the cap 32 has been removed by unscrewing the stem 33 from said bushing. The bushing 27 and contacting finger 30 are designed to receive a standard plug, such 50 for example as the plug 35, and current will pass through the wire 36 in the usual manner; it being noted that the upper end of the plug engages the contacting finger 30. Thus an electric device can be connected to my improved electrolier without disturbing or removing any of the bulbs from the main lamps 12 and at the same time the electrolier is not rendered unsightly since the connecting wire to the device leads centrally downward from the electrolier which does not affect the ornamental appearance of the electrolier.

In the form of my invention shown in Fig. 6 instead of having a cap provided 60 with a screw threaded stem which is screwed

into the bushing 27, I provide a cap 32^a which is hinged at 37 to the bottom of the shell 18^a of the tassel and provide said cap 32^a with a lip 38 adapted to be secured by a spring 39 located entirely within the shell 70 18^a. Thus when it is desired to attach a connecting plug, such as the plug 35, it is merely necessary to pull the cap 32 downwardly to release the lip 38 from the spring 39 and the cap 32^a will swing into a position 75 such as shown in dot-and-dash lines in Fig. 6 and said plug 35 can then be screwed into the bushing 27. In all other respects the construction of Fig. 6 is similar to that described in connection with Figs. 1 to 5 80 inclusive and I have therefore given similar parts corresponding reference numerals.

While I have described my invention as taking a particular form, it will be understood that the various parts of my invention may be changed without departing from the spirit thereof, and hence I do not limit myself to the precise construction set forth, but consider that I am at liberty to make such changes and alterations as fairly 90 come within the scope of the appended claims.

Having thus described my invention, what I claim as new and desire to secure by Letters Patent is:—

1. An electrolier including a depending tassel having a hollow external shell provided with a hole at its top, a tube extending through said hole and having a portion projecting above said shell and another portion extending into the space within said shell, a looped head secured to the projecting portion of said tube; means providing contact members located within said shell and attached to said tube within the shell 100 whereby electric conduit wires can connect with said contact members by entering through the looped head and tube, and means forming a connection for said head to another portion of the electrolier whereby 105 the tassel is supported independently of the electric wires; substantially as described.

2. An electrolier having a centrally depending tassel, said tassel being hollow and having electric contacting members therein 115 whereby a connecting plug of an electric device can be held in engagement with said contacting members, said tassel including a hole in its bottom to permit the insertion of said plug into engagement with said contacting members; and a detachably connected cap for covering said hole and forming a part of the design of said tassel; substantially as described.

3. An electrolier including a depending 125 tassel having a hollow external shell and a looped head, said shell having a hole communicating with the opening of said head; a tube extending downwardly within said tassel shell in alignment with said hole in 130

the shell; means providing contact members connected to said tube within the shell and electric wires leading from said contact members through said tube and hole and outwardly through the opening in said looped head; and means forming a connection for said looped head to another portion of the electrolier; substantially as described.

In testimony whereof I have signed my name to this specification in the presence of 10 two subscribing witnesses.

ROBERT J. WARD.
